UNITED STATES PATENT OFFICE.

HENRY C. BEMAN, OF MEADVILLE, PENNSYLVANIA.

OIL-CAN.

No. 860,276.

Specification of Letters Patent.

Patented July 16, 1907.

Application filed November 19, 1906. Serial No. 344,188.

To all whom it may concern:

Be it known that I, HENRY C. BEMAN, residing at Meadville, in the county of Crawford and State of Pennsylvania, have invented a new and Improved 5 Oil-Can, of which the following is a specification.

My invention relates to certain new and useful improvements in oil cans and it particularly seeks to provide a can having means whereby the same can be used to fill lamps and the like, and which has provisions in virtue of which the flow of oil to the lamp will be automatically cut off as soon as the lamp or other oil receiver is full.

In its generic nature my invention embodies an improved can having a receiving aperture in the top 15 closed by a screw cap and a pouring spout carried by the top of the can having valve mechanism within itself and air vent ducts together with a pouring duct and arranged whereby when the spout is in one position the pouring and air ducts of the spout will register 20 with corresponding apertures or ducts of the can and permit the contents of the can to flow out as air flows in.

My invention also includes a stop carried by the spout for limiting the distance to which it can be inserted into the filling aperture of the lamp or other 25 similar receptacle. A carrying handle is also provided on the top of the can and a supplemental handle on the wall of the can and in some instances means are provided for supporting the can on trunnions when the same is of very large capacity.

30 In its more detail features my invention comprises certain novel construction, combination and arrangement of parts all of which will be first described in detail, and then be specifically pointed out in the appended claims, reference being had to the accompanying drawings, in which:—

Figure 1, is a perspective view of a can embodying my invention with the pouring spout in the position it assumes when closed. Fig. 2, is a perspective view showing the application of my invention for filling 40 lamps with the pouring spout in its filling position. Fig. 3, is a central, vertical, longitudinal section of the upper portion of the can. Fig. 4, is a detail perspective view of the spout detached. Fig. 5, is a similar view of the can carried member to which the spout is 45 adapted to be attached. Fig. 6, is a detail cross section of the spout and the can carried member to which it is attached when in the pouring position. Fig. 7, is a central, vertical, longitudinal section of the filling 50 aperture portion of the can. Fig. 8, is a detail view of a slightly modified form of my invention. Fig. 9, is a rear elevation of the can carried valve member showing nut locking means. Fig. 10, is a longitudinal section of the spout.

Referring now to the accompanying drawings in

which like letters and numerals of reference indicate 55 like parts in all of the figures, it will be seen that 1 designates the can body which may be of any approved construction, *per se*, but which is preferably formed of galvanized iron and provided with peripheral corrugations 1^a spaced apart at suitable intervals to give 60 strength to the can body. The bottom of the can body 1 may also be corrugated, as shown in annular corrugations.

The top 3 of the can body is provided with a carrying handle 4 and a pouring aperture 3^a surrounded by a 65 screw threaded nipple 3^b to receive the closure cap 5 which carries the washer 5^a within the same and is provided with a winged member 5^b by means of which the cap can be screwed onto the nipple 3^b. The washer 5^a is held in place by a disk 5^c soldered or 70 otherwise secured to the cap 5 through an aperture in the disk 5^a, as indicated.

6 designates a handle member secured near the bottom of the can on the side thereof, as shown.

7 designates a member which comprises the annular 75 valved disk portion 7^a, the air vent portion 7^b and the pouring duct 7^c as shown, the member 7 being formed by casting the same or otherwise, and secured to the can through the medium of a base portion 7^d formed therewith.

The air duct 7^b terminates in an angle portion 7^e running parallel with the top of the can inside the same. The angle or elbow member 7^e carries a pipe section 8 which runs to the side thereof opposite the can carried spout coöperating member 7. The air vent duct 7^b 85 has its upper wall 7^x arranged to form a shoulder with the upper wall 7^y of pouring duct 7^c, for a purpose presently explained.

The valve portion 7^a of the member 7 is centrally apertured as at 7^f to receive a securing bolt 9 while the 90 outer face of the valve member 7^a is countersunk as at 7^g to receive a washer 9^a against which the securing nut 9^b for the bolt 9 rests, the shoulder portion 7^x and 7^y of the vent and pouring ducts 7^b and 7^c respectively form a lock for the nut 9^b as indicated. 95

10 designates the pouring spout which comprises the valve portion 10^a having a pouring port 10^m that co-operates with the pouring port 7^m of the pouring duct 7^c and the valve member 10^a has an air port 10ⁿ that co-operates with the air port 7^b of the member 7. 100

10^b designates an air duct passing through the spout 10 from the outer end thereof and communicating with the port 10ⁿ while the port 10^m communicates with the pouring duct 10^c of the spout 10 which runs parallel with the air duct 10^b through the spout proper. 105

The valve portion 10^a in the spout member 10 is countersunk on its outer face as at 10^d and apertured as at 10^e to permit passage of the securing bolt 9, a coil

spring 11 being interposed between the head of the bolt 9 and the coöperating wall of the countersunk portion 10^a of the spout member.

The spout member 10 has its spout portion provided 5 with a lug 12 for engaging the edge of the lamp body to prevent the insertion of the spout into the lamp beyond a predetermined distance.

In the practical operation of my invention it will be noticed that the adjacent faces of the valve portions of 10 the spout member 10 and that of the can carried member 7 are smooth and lie close up against each other to effect a liquid tight joint, the coil spring 11 serving to aid in holding the two portions of the valve member always tightly together while terminating the pivotal 15 movement of the spout in the securing bolt.

So far as described the manner in which my invention operates is best explained as follows: The can after being filled in the usual manner through the filling opening thereof has the cap 5 screwed tightly in 20 place so as to make an air-tight joint between the cap and the can and the spout member drawn back into the position shown in Fig. 1. This causes the ports in the spout portion of the valve mechanism to be moved out of register with those of the can carried portion of 25 the valve mechanism and thus the can is air-tight and all danger of spilling the liquid therefrom is avoided. When it is desired to fill a lamp or other similar device then the spout 10 is swung down as shown in Fig. 2 to bring its ports in register with the ports of the member 30 7. The can is then tilted forward with the spout inserted in the lamp as far as it will go, *i. e.*, until the lug 12 engages the lamp body. The oil runs freely until it rises sufficiently in the lamp to cover the end of the spout, thus sealing off the air and thus stopping 35 the flow. The can is then tilted slightly backward which drains the spout and prevents any drip whatever. The spout or filling tube is then swung over the top of the can into the position shown in Fig. 1, and thus the can is closed air-tight, while the filling 40 spout is also simultaneously protected from all possible injury by rough handling.

In Fig. 8, I have shown a slightly modified form of my invention in which the can is provided with a rod 13 that passes therethrough and projects slightly out 45 side of the same. This rod 13 forms a fulcrum and is secured in bearings 14^a on a supporting stand 14 of any approved type, thus permitting the can to be turned as on a trunnion to fill the lamps or other receptacles, it being understood that this form of my invention 50 is particularly adapted for use with cans of large capacity.

From the foregoing description taken in connection with the accompanying drawings it is thought the complete construction, operation and many advantages of my invention will be readily understood by those skilled in the art to which it appertains and I desire to say that many slight changes in the detail 55

construction, combination and arrangement of parts may be made without departing from the spirit of my invention or the scope of the appended claims. 60

What I claim is:—

1. A can comprising a can body having a filling aperture, a closure cap for said filling aperture, a can carried valve member having a pouring duct and a vent duct, said valve member formed of an integral structure, and 65 having ports for said pouring and vent ducts, a spout member formed of an integral structure and having a pouring duct and a vent duct, and ports therefor, means for pivotally connecting the spout member to the can carried valve member to swing in a vertical plane, all being 70 arranged so that when the spout member is swung back over the can the ports thereof will be out of communication with the port of the can carried valve member and when the spout member has swung out from the can the ports thereof will be in communication with those of the 75 can carried valve member said can carried valve member and said spout member having flat engaging faces lying in parallel contacting planes when the members are assembled, substantially as shown and described.

2. A can comprising a can body having a filling aperture, a closure cap for said filling aperture, a can carried valve member having a pouring duct and a vent duct, said valve member formed of an integral structure and having ports for said pouring and vent ducts, a spout member formed of an integral structure and having a pouring duct 85 and a vent duct and ports therefor, means for pivotally connecting the spout member to the can carried valve member to swing in a vertical plane, all being arranged so that when the spout member is swung back over the can the ports thereof will be out of communication with 90 the port of the can carried valve member and when the spout is swung out from the can the ports thereof will be in communication with those of the can carried valve member, and a vent tube connected with the can carried valve member and in communication with the vent duct thereof, 95 and passed across the top of the can within the same, said can carried valve member and said spout member having flat contacting faces lying in parallel planes when the members are assembled, substantially as shown and described. 100

3. A can comprising a can body having a filling aperture, a closure cap for said filling aperture, a can carried valve member having a pouring duct and a vent duct, said valve member formed of an integral structure, and having ports for said pouring and vent ducts, a spout member 105 formed of an integral structure and having a pouring and a vent duct therefor, means for pivotally connecting the spout member to the can carried valve member to swing in a vertical plane, all being arranged so that when the spout member is swung back over the can ports thereof will be out of communication with the ports of the can carried valve member and when the spout member has swung out from the can the ports thereof will be in communication with those of the can carried valve member, said means for pivotally connecting the spout member to the 110 can carried valve member comprising a bolt and nut and a spring for holding the spout and valve members together, said can carried valve member having seats to engage the nut and said spout member having a pocket to receive the spring all being arranged substantially as 115 shown and described. 120
